United States Patent Office

Des. 216,865

Patented Mar. 17, 1970

216,865

COMBINED LUGGAGE HANDLE AND STUDS THEREFOR

Anthony N. D'Elia, New York, and Edward M. Stolarz, Yorktown Heights, N.Y., assignors, by mesne assignments, to Presto Lock Co., Inc., Garfield, N.J., a corporation of Delaware

Filed July 2, 1968, Ser. No. 12,599

Term of patent 14 years

Int. Cl. D8—03

U.S. Cl. D8—154

FIG. 1

FIG. 2

FIG. 3

FIG. 4

FIG. 1 is a top plan view of a combined luggage handle and studs therefor embodying our new design; FIG. 2 is a side elevational view;

FIG. 3 is an end view; and

FIG. 4 is a bottom plan view.

We claim:

The ornamental design for a combined luggage handle and studs therefor, as shown.
